UNITED STATES PATENT OFFICE.

JOHN E. NATHAN, OF NEW YORK, N. Y.

SNOW-PLOW.

SPECIFICATION forming part of Letters Patent No. 339,680, dated April 13, 1886.

Application filed September 11, 1885. Serial No. 176,791. (No model.)

To all whom it may concern:

Be it known that I, JOHN E. NATHAN, a citizen of the United States, residing at New York, in the State of New York, have invented 5 certain new and useful Improvements in Snow-Plows, of which the following is a specification.

The object of my invention is to construct a plow for removing snow from railroad-tracks; 10 and my invention consists in the features and details of construction hereinafter described and claimed.

In the drawings, Figure 1 represents a side elevation of my improved snow-plow. Fig. 2 15 represents a plan view of the same, and Fig. 3 represents a front elevation.

A represents the top one of my series of snow-plows; B, the one next below; C, the one next below it; D, the bottom one of the series, 20 and E the car to which the snow-plows are attached.

In making a snow-plow of my construction I use a series of two or more plows mounted one above the other, and the top one farthest 25 in advance. Each one of the plows in the series is provided with an inclined chute or sloping surface, by which the snow is carried back and outward from the center toward the sides, so that it will be deposited at either side of 30 the track. The general form and outline of these plows forming the series need not differ materially from the general form and configuration of snow-plows as ordinarily constructed; but the snow-plow is made in a series of 35 plows, each one advanced beyond the other from the lowest to the highest, so that as the car is propelled or advanced into the snow-drift the upper plow will remove the top portion or section of the drift, thus diminishing 40 its height before the next plow has entered the drift. In this way the height of the drift will be diminished as each plow successively reaches it, so that by the time the last one of the plows 45 has reached the drift there will remain but a small depth of snow to be removed. In this

respect my snow-plow differs from any I have ever seen or of which I have ever heard. Where the snow-plow enters the drift, as is ordinarily the case, at the bottom without having removed any of the snow from the top, 50 so that the whole depth of the drift is required to be removed at once, the plow necessarily packs and presses the snow together, so that it becomes impossible to propel the car or engine to which the plow is attached forward and 55 raise and remove the snow; but by removing a portion of the drift at a time, beginning at the top, no difficulty of this nature is to be encountered.

I am aware that snow-plows have been made 60 with inclined ways arranged one behind and below the other from front to rear, provided with internal chutes for conveying the snow to the top of the plow to be thrown off by V-shaped wings. I also acknowledge the existence 65 of snow-plows provided with chutes arranged one above the other, and projecting forward one beyond the other to the top, provided with wings or conveyers for the snow on the outside, arranged to discharge the snow 70 from the side on or near the line at which it was taken on the plow. These features I wish to disclaim.

What I desire to claim and secure by Letters Patent is—

A railway snow-plow consisting of two or more plows arranged one above the other in a continually-advancing series from the lowest plow, the lowest plow being the farthest back, and each succeeding plow being advanced beyond the one immediately below it, and each plow being provided with a continuous external channel extending to the top of the elevation of the snow, whereby the snow will be removed in successive layers, beginning at the 85 top, substantially as described.

JOHN E. NATHAN.
